R. W. LOFSTROM.
SAFETY DEVICE FOR LADDERS.
APPLICATION FILED MAR. 28, 1917.

1,243,844.

Patented Oct. 23, 1917.

By Watson E. Coleman

Attorney:

UNITED STATES PATENT OFFICE.

ROBERT W. LOFSTROM, OF WORCESTER, MASSACHUSETTS.

SAFETY DEVICE FOR LADDERS.

1,243,844.

Specification of Letters Patent. Patented Oct. 23, 1917.

Application filed March 28, 1917. Serial No. 158,008.

To all whom it may concern:

Be it known that I, ROBERT W. LOFSTROM, a citizen of the United States, residing at Worcester, in the county of Worcester and State of Massachusetts, have invented certain new and useful Improvements in Safety Devices for Ladders, of which the following is a specification, reference being had to the accompanying drawings.

10 This invention relates to an improved safety device for ladders and has for its primary object to provide a very simply and durably constructed ladder attachment whereby the ladder will be securely held 15 against accidental shifting movement upon the floor or ground surface and possible injury to the person ascending or descending the ladder thus obviated.

It is one of the important objects of the 20 invention to provide a device for the above purpose which will effectively operate to hold the ladder in position upon a metal or concrete floor, as well as upon wooden floors.

More particularly stated, the invention 25 embodies an attachment for each of the ladder rails consisting of fixed body plates and an anchoring or holding device pivotally mounted between the body plates, said anchoring plates being adjustable to different 30 relative positions for properly supporting the ladder upon a metal, concrete, or wood floor surface, and means mounted upon the body plates with which said holding plates are adapted to engage to prevent the 35 accidental movement of the latter from their adjusted positions.

With the above and other objects in view, 40 my invention consists in the novel features of construction, combination and arrangement of parts to be hereinafter more fully described, claimed and illustrated in the accompanying drawing, in which,

Figure 1 is a side elevation showing my 45 improved safety device applied to the lower end of a ladder rail, several adjusted positions of the holding plate being illustrated in dotted lines;

Fig. 2 is a front elevation of the attachment; and

50 Fig. 3 is a section taken on the line 3-3 of Fig. 1.

Fig. 4 is a side elevation illustrating a slightly modified form of the device; and

55 Fig. 5 is a section taken on the line 5-5 of Fig. 4.

Referring in detail to the drawing, 5

designates a pair of metal plates which are arranged upon each other and securely bolted at one of their ends, as at 6, to the outer side of the ladder rail R. These 60 plates project below the lower end of the rail R and are transversely offset in relatively opposite directions, as shown at 7, to space apart their lower end portions 8. The offsets 7, at opposite sides of the central 65 line of the plate, are obliquely extended in relatively opposite directions to the longitudinal edges of the plate, whereby inclined bearing shoulders 9 are formed. Adjacent to these bearing shoulders, the two plates 5 70 are permanently riveted together, as at 10.

Between the lower spaced end portions of the plates 8, the anchoring or holding plate 11 is disposed and engaged for pivotal movement upon a bolt 12 connecting said 75 spaced portions 8 of the body plates. This holding plate 11 is preferably of triangular form, as shown, and the base edge thereof is longitudinally recessed or cut away, as at 13, said recess terminating before it 80 reaches the points or apices 14 of the plate. Thus, the spaced apart foot portions 15 are formed, which provides spaced apart points of frictional contact of the edge of the plate disposed upon opposite sides of the pivotal 85 axis thereof, when the ladder is set in position upon a metal or concrete floor surface as shown in full lines in Fig. 1. These narrow feet 15 exerting a frictional bearing pressure upon the relatively smooth floor 90 surface will effectively hold the ladder against spreading or swinging movement.

To the body plates 5 above the shoulders 9, metal loop straps 16 are pivotally connected at their extremities by the rivets 17. 95 These metal loops project in opposite directions with respect to the body plates and normally rest upon the outer ends of the offsets 7 in the body plates.

When the ladder is used upon a wooden 100 floor surface, the plates 14 may be turned to the positions indicated in dotted lines at A in Fig. 1, so that one of the points 15 will be in the vertical line of the pivot 12. One of the loops 16 is then engaged over the 105 other point 14 of the plate to hold said plate in this adjusted position. The downwardly projecting point 14 of the plate will embed itself in the floor surface under the weight of the person ascending the ladder and thus 110 prevent shifting movement of the same, or the plate may be disposed in the dotted line

position B, with one of its points 14 disposed in advance of the pivot 12 and the other of the loops 16 engaged over the other point of the plate. Should the floor surface be uneven, the plate 11 at one side of the ladder may be disposed in position A, while the plate on the opposite side of the ladder is disposed in position B. It is to be particularly noted that in either of these latter positions of the plate 11, the same abuts against the shoulders 9 on the body plates, and there is no strain upon the loops 16 or the pivot connections 17 thereof, said loops simply acting as stops to prevent an outward swinging movement of the plate 11 with respect to the shoulders 9 and also to prevent the accidental displacement of the plate by falling objects striking its upwardly projecting point or by striking the same with the foot when descending the ladder. These loops also retain the plates 11 in their adjusted positions when the ladder is moved from place to place.

Referring now to Figs. 4 and 5 of the drawing, wherein I have shown a slightly modified form of the device, 11' designates the holding or anchoring plate which is similar in configuration to the anchoring plate above described. One of the plates 11', however, is adapted to be secured to the upper end of each of the ladder rails upon either the inner or outer face thereof, by means of the bolt 12'. In order to securely hold the plate 11' and prevent turning movement of the same upon or with the bolt 12', an opening is punched in the plate with a suitable tool to project the metal from one face of the plate, as shown at 20. This projection is disposed in line with the bolt receiving opening in the plate and is adapted to be embedded in the ladder rail, as clearly shown in Fig. 5 of the drawing. In order to prevent splitting of the rail, a bolt indicated at 21 may be inserted transversely through the upper end thereof. This modified form of the anchoring plate is particularly adapted for the purpose of holding the upper end of the ladder against either vertical or lateral movement with respect to the face of a wall or post against which the ladder is disposed, and also to afford further security when the ladder is used upon a very hard and smooth floor surface to prevent displacement of the ladder in case the lower end portion thereof should be accidentally struck.

In Fig. 4, I have shown the ladder disposed at its upper end against a rod or shaft S running along the face of the wall indicated at W. One end or the other of the plate 11', according to whether this plate is arranged upon the inner or outer face of the ladder rail, is disposed over and upon the shaft S, and the point of the plate 65 is embedded in the wall face. Thus, the

ladder at its upper end will be effectually held against either vertical or lateral shifting movement. It will, of course, be understood that in either form of the plate 11, the lower edges of its foot portions 15 may be toothed or otherwise formed in order to obtain a more securely gripping engagement with the surface.

From the foregoing description, taken in connection with the accompanying drawing, the construction, manner of use, and several advantages of the device will be clearly and fully understood. It will be seen that I have provided a very simple and durably constructed ladder attachment whereby the 75 ladder is effectively held against shifting or sliding movement either upon smooth, concrete, or metal floors, or upon a wood floor. The holding plates may be very easily and quickly adjusted in order to properly position the ladder. In view of the 80 very simple construction of the attachment, it is also manifest that the same can be produced at small manufacturing cost.

While I have herein shown and described 90 the preferred construction and arrangement of the several elements employed, it is apparent that the same are susceptible of considerable modification and I, therefore, reserve the privilege of adopting all such 95 legitimate changes as may be fairly embodied within the spirit and scope of the invention as claimed.

Having thus fully described my invention, what I desire to claim and secure by 100 Letters Patent is:

1. A device of the character described comprising a pivotally mounted, triangular floor engaging plate having spaced points for engagement with the floor surface, and means to operatively engage one of the points of said plate and hold the other in vertical alinement with the pivot of the plate for operative engagement with the floor surface.

2. A holding device of the character described comprising a relatively fixed body, a holding plate movably mounted upon said body and having spaced floor engaging points, said plate being adjustable with respect to the body to position either of said points for engagement with the floor surface, said body having stop shoulders with one of which said adjustable plate has bearing engagement in either of such positions.

3. The device recited in claim 2, further characterized by latch members mounted on the body to engage the plate and hold the same against said stop shoulders.

4. The device recited in claim 2, further characterized by latch loops pivoted upon the body for engagement with the inactive point of said plate in the operative position of the plate.

5. A holding device for ladders including 130

a pair of plates bolted to the ladder rail and being offset to space the plates apart at one of their ends, a holding plate pivotally mounted between the spaced ends of the body plates and adjustable to various positions between said body plates for operative engagement with the floor surface, and latch devices mounted upon the body plates to engage the holding plate in certain of its operative positions and prevent pivotal movement thereof.

6. A holding device for ladders including a pair of body plates fixed to the lower end of the ladder rail and having offset portions to space said plates apart at one of their ends, said offset portions providing stop shoulders, a holding plate of polygonal form pivotally mounted between the spaced ends of the body plates and adjustable therebetween to various positions for operative engagement with the floor, said holding plate in certain of the operative positions thereof bearing against the stop

shoulders which limit the pivotal movement of the plate in one direction, and latch elements mounted upon the body plates to contact with the holding plate in such operative positions of the plate and prevent pivotal movement of said holding plate in an opposite direction.

7. A device of the character described comprising a substantially triangular-shaped plate, an attaching bolt therefor, and means for holding the plate against pivotal movement with respect to the part to which it is attached, whereby either one of two spaced apices of the plate may be disposed in operative position with respect to said part.

In testimony whereof I hereunto affix my signature in the presence of two witnesses.

ROBERT W. LOFSTROM.
